[57] CLAIM

The ornamental design for a sun shade for a lawn chair or the like, as shown and described.

DESCRIPTION

FIG. 1 is a front and bottom perspective view of a sun shade for a lawn chair or the like showing our new design;

FIG. 2 is a top plan view thereof;

FIG. 3 is a bottom plan view thereof;

FIG. 4 is a right side elevational view thereof, the left side elevational view being a mirror image of that shown; and

FIG. 5 is a front elevational view thereof.

FIG. 1

FIG. 2

FIG. 3

FIG. 4

FIG. 5
